KNIFE SHARPENER

Harland R. Ransom, Detroit, Mich.

Application May 31, 1946, Serial No. 673,232

3 Claims. (Cl. 76—86)

1

This invention relates to sharpening devices, and more particularly, relates to a sharpener for knife blades or other straight-edge tools which is of novel and improved design. In certain respects the invention constitutes an improvement over that embodied in my Patent No. 2,038,445.

It is the primary object of the present invention to provide a knife sharpener of novel and improved design which may be safely used by those having little or no experience in sharpening knives or straight-edge tools to easily and quickly sharpen such instruments.

The present invention further contemplates a sharpening device of the character described which may be used to thus sharpen a knife without damaging the original bright finish of the blade.

A further object of the present invention is to provide a sharpener construction which may be used for sharpening blades of scissors.

Further objects and advantages of my invention will be apparent from the description which follows when considered in connection with the accompanying drawings in which like numerals indicate like parts wherever shown and wherein:

Fig. 1 is a perspective view of a knife sharpener embodying improvements of the present invention, illustrating the use of the same for sharpening a knife blade;

Fig. 2 is a section taken on line 2—2 of Fig. 1, illustrating one of the sharpening elements disposed in a trough-like depression in the mounting portion of the sharpener and the bottom surface of such depression continued to form a forwardly directed tab;

Fig. 3 is a section taken on line 3—3 of Fig. 1, illustrating another sharpening element in another trough-like depression provided in the mounting portion of the sharpener and showing the slot in the lower surface of such trough in which the mounting bolt for securing such sharpening element is adapted to slidably move;

Fig. 4 is a section taken on line 4—4 of Fig. 1, illustrating the U-shaped formation of the handle of the sharpener;

Fig. 5 is a section taken substantially on line 5—5 of Fig. 1, illustrating the relative depth of the troughs adapted to receive the sharpening elements and the overlying relationship of one end of one of said sharpening elements with respect to an end of the other such element;

Fig. 6 is a perspective view of the sharpening

device illustrated in Fig. 1 used to sharpen a blade of a scissors.

According to the present invention a pair of sharpening elements arranged in the form of a V, open at the top, are secured to a mounting portion of the frame of the sharpening device and receive the blade of a knife therebetween. A handle is provided integral with this mounting portion and means are also provided on such frame to serve as a standard whereby the sharpener may be positioned on a table top and held thereagainst when the handle is grasped, allowing the user thereof to insert the knife blade and sharpen the same quickly and easily without injury to the user or damage to the blade finish.

The sharpener of this invention may also be used with the handle thereof in substantially upright position, positioned in such manner that an exposed portion of the side of one of the sharpening elements is available for sharpening the blades of scissors.

In order to more fully describe the sharpener of this invention, reference is made to the figures, and particularly to Fig. 1, in which a frame having a mounting portion 10 is shown. At the right of this mounting portion a U-shaped handle portion 12 is formed integral therewith. On the forward end of the mounting portion 10, which is at the left as viewed in Fig. 1, a wing 14, shown best in Fig. 3, is turned rearwardly with respect to the face thereof. Also, at the right of the mounting section, a wing 16, which is co-extensive with one of the sides of the U-shaped handle 12, is turned rearwardly with respect to the face of mounting portion 10.

In order to mount the sharpening elements 18 and 20, the forward face of the mounting portion 10 is provided with the trough-like depressions 22 and 24, in the form of a V, open at the top. To provide rigidity for the structure at this point, such depressions are reinforced as indicated at 26 and 28, respectively. These depressions or troughs 22 and 24 have different depths, as may best be seen in Fig. 5, and shallow trough 22 terminates at the closed end of the V thus formed, by merging into one side of the deeper trough 24. Elements 18 and 20 preferably are generally rectangular in form so that they seat solidly in and are retained by the depressions 22 and 24 and they conveniently can be made of hardened steel or the like.

It will be observed, that when sharpening elements 18 and 20 are disposed within their respective troughs, one end of sharpening element 55 18 extends in overlying relationship to an end of

sharpening element 20. Thus, in this manner, when the sharpening element 18 is secured within trough 22 by means of bolt 30 and nut 32, such sharpening element serves to retain the sharpening element 20 in trough 24.

To provide for shifting of the sharpening elements when the same become worn, bolt 30 is slidably positioned within a slot 34 provided in the bottom surface of trough 22. Obviously, upon loosening nut 32, sharpening element 18 becomes free to move to the extent permitted by such slot 34, and sharpening element 20 will be free to move in trough 24, so that such sharpening elements may be shifted when the same becomes dull through use. However, it is pointed out, that the angularity between the sharpening elements remains constant inasmuch as the same are constantly held within their respective troughs and hence the angle between the same cannot be varied, although such elements may be shifted. It is further pointed out that should the entire lengths of these sharpening elements become dull on one edge, the same are so designed and constructed that they may be turned over to use the other edge.

The previously described wings 14 and 16 form, in effect, two side walls of a triangular standard by means of which the sharpener of this invention may be supported on a table top or other flat surface. To provide a third supporting element of such standard, the bottom surface of the deep trough 24 is continued and permitted to extend forwardly forming a tab 36. From Figs. 2 and 3, it will be appreciated that the lower surface of this tab 36 lies in the plane of the lower edges of wings 14 and 16, and that the forward face of mounting portion 10 is angularly inclined with respect to such plane. Consequently, by grasping the handle the sharpener may be supported rigidly and positively with the face thereof inclined at an angle with respect to a table top or other surface by means of such standard. The angle at which the face of the sharpener is thus disposed, may be any angle which brings the forward faces of the edges of the sharpening elements 18 and 20 into position to contact the blade of a knife or other straight-edge tool without permitting such blade to contact the bottom of the V formed by said sharpening elements.

With the sharpener supported on a table top or other flat surface in the manner described in the foregoing, the blade of a knife indicated at 38 may be placed between such sharpening elements 18 and 20 and said blade drawn from the handle of the knife to the point thereof for sharpening the same. It may be appreciated now that normally the user will grasp handle 12 with the left hand and then draw the knife 38 in the direction indicated by the arrow on the knife blade in Fig. 1. Thus, each hand of the user is well away from danger and the varying width of the V space between the edges of the sharpening elements is sufficient to prevent injury to the polished sides of a knife blade.

For sharpening blades of scissors, the sharpener may be mounted on a table or other flat surface in the position shown in Fig. 6, using the outer surface of wing 14 as a standard therefor. A notch 40 is formed in one side of trough 24, beside the handle 12 exposing an edge of the sharpening element 20. A blade 42 of the scissors is inserted in this notch and held against the adjacent side edge of the handle 12 in contact with the side of the sharpening element 20 and

drawn from the heel to the point thereof to sharpen the same. During the drawing or sharpening operation, the handle positions and guides the blade for proper engagement with the sharpening element.

From the foregoing, it will be appreciated that with a sharpener embodying the improvements of the present invention it is possible to quickly and easily sharpen a knife or straight-edge tool without injury to the user and without in any way marring the finish on the sides of the blade.

It will be clear from the foregoing description that the sharpener shown in the drawings and described above has been illustrated and described in rather specific detail. Obviously, many modifications, changes, and departures from the above described construction may be made without departing from the generic spirit and scope 20 of the invention as set forth in the subjoined claims.

What is claimed is:

1. A sharpener including, in combination, means comprising a mounting portion, a handle 25 integral therewith, a forwardly directed tab and rearwardly directed wings on said mounting portion, one of said wings extending substantially at right angles to said handle and the lower surface of said tab located in the plane of the lower edges 30 of the wings, said tab and wings forming a standard to support the sharpener on a flat surface with the face thereof inclined with respect thereto when the handle is grasped; sharpening elements on said mounting portion arranged to 35 form an open V for receiving the blade of a straight-edge tool therebetween; and a notch in said mounting portion adjacent said handle, said notch extending behind an edge of one of said sharpening elements and located to be readily accessible when the sharpener is supported solely on said right-angularly extending wing.

2. A sharpener including, in combination, means comprising a mounting portion having 45 trough-like depressions formed therein in the shape of a V open at the top with one of said depressions being deeper than the other and having the bottom surface thereof continued to form an outwardly directed tab, a handle integral with the mounting portion, rearwardly directed 50 wings formed on the mounting portion with the bottom surface of said tab located in the plane of the lower edges of the wings, said tab and wings serving as a standard for supporting the sharpener on a flat surface when the handle is grasped; and sharpening elements disposed in said depressions with an end of one element in overlying relationship to an end of the other element.

3. A sharpener including, in combination, 60 means comprising a mounting portion having trough-like depressions formed therein in the shape of a V open at the top with one of said depressions being less deep than the other and terminating at one side of the deeper depression, the bottom surface of said deeper depression being continued to form an outwardly directed tab, a handle integral with said mounting portion, rearwardly directed wings formed on said mounting portion with one of said wings coextensive with 65 the side of said handle, the bottom surface of said tab being in the plane of the lower edges of said wings, said tab and wings forming a standard adapted to support the sharpener on a flat surface with the face thereof inclined with respect to 70 said surface when the handle is grasped; and a 75

sharpening element shiftably disposed in each depression.
